FOLDABLE SHOE TREE HAVING MEANS FOR ENGAGING THE HEEL OF A SHOE

John H. Myers, St. Paul, Minn., assignor to Waldorf Paper Products Corporation, St. Paul, Minn., a corporation of Minnesota

Application October 29, 1952, Serial No. 317,432

1 Claim. (Cl. 12—128)

This invention relates to an improvement in shoe tree and deals particularly with a device useful in holding a shoe in proper shape and which can be quickly and easily produced.

It has long been recognized that shoes will retain their shape more effectively when shoe trees are placed therein. The more expensive shoes on the market are provided with shoe trees between the time they are produced and the time they are sold. However, in view of the cost of such shoe trees, it is impractical for less expensive shoes to be shipped in this manner.

An object of the present invention resides in the provision of a shoe tree which can be inexpensively produced and sold. These shoe trees are formed of paperboard or similar material and are die cut to the proper shape and size. When inserted in a shoe they tend to hold the instep of the shoe fully expanded to prevent a crease from forming at this point of the shoe. The shoe trees also tend to hold the sole of the shoe from curling upwardly during shipment and storage.

A feature of the present invention resides in the fact that the shoe trees made in accordance with my invention are extremely light in weight and accordingly may be shipped economically. Shoe trees of more conventional types are made of wood and are relatively heavy, thereby adding considerably to the shipping weight of the shoes.

A further feature of the present invention lies in the fact that my shoe trees may be produced in various sizes and economically stored prior to use and may be economically shipped to the shoe factory or other user. When produced the shoe trees are flat and relatively thin and accordingly a considerable number of shoe trees may be contained in a small area.

A further feature of the present invention resides in the fact that my shoe trees tend to conform to the shape of the shoe as they are inserted and thus are easier to insert than shoe trees of conventional types. When the flat body is inserted into the shoe the side edges of the flat body tend to fold downwardly into engagement with the sole of the shoe, thus bending the body into a trough shaped or channel shaped form. While the paperboard in flat form may be bent with comparative ease, the structure assumes considerable strength when bent into trough shaped formation, thereby withstanding the force which is placed upon them.

A further feature of the present invention resides in the provision of a shoe tree comprising a flat body of sheet material having a series of longitudinally extending score lines therein which assist the folding of the sheet into trough shaped form. These score lines tend to flex the flat body in the desired direction rather than in a transverse direction and assist in forming the tree to the proper shape as it is inserted.

These and other objects and novel features of my invention will be more clearly and fully set forth in the following specification and claims.

In the drawings forming a part of the specification:

2

Figure 1 is a plan view of the shoe tree in flat formation.

Figure 2 is a perspective view of the shoe tree as it would appear in use.

5 Figure 3 is a bottom perspective view of the shoe tree showing the general construction thereof.

Figure 4 is a perspective view showing the shoe tree in place within a shoe.

The shoe tree is indicated in general by the letter A 10 and is designed for use in a shoe indicated in general by the letter B. When formed, the shoe tree is substantially flat and accordingly may be economically stored and shipped.

The shoe tree A is formed of paperboard or similar 15 material. The material most commonly employed comprises a laminated sheet of paperboard which may range from $\frac{1}{20}$ to $\frac{1}{10}$ of an inch in thickness, although the board need not necessarily come within these limits. The body includes a rounded front end 10 which is curved 20 at a radius greater than the usual radius of curvature of the toe portion of the shoe in which it is used. The curved forward end extends perhaps $\frac{1}{3}$ of the total length of the shoe tree, the widest part of the shoe being indicated at 11 at a point spaced rearwardly from the curved forward end 10. From the widest point 11, the 25 sides of the body curve inwardly as indicated at 12. The curved portions 12 preferably end in a notch 13 on each side of the body. An inwardly tapered handle portion 14 projects beyond the notches 13 in the preferred form of construction.

In order to simplify the forming of the body, I preferably provide longitudinally extending fold lines extending from the handle portion to the curved toe portion. In the particular embodiment illustrated, two fold lines 15 35 and 16 are spaced in opposite sides of the longitudinal center of the body and are substantially parallel. A second pair of fold lines 17 and 19 also extend from the handle portion 14 to the toe portion 10, these lines preferably diverging apart slightly from the handle portion 40 toward the toe portion. Additional fold lines 20 and 21 may be provided in pairs outwardly of the fold lines 19 and 20. Due to the spacing between the fold lines certain of the outer fold lines 20 and 21 may not extend the full length of the body.

When it is desired to insert the shoe tree A into the 45 shoe B, the flat body sheet is usually bent into channel form as indicated in Figures 2 and 3 so as to prebreak the various score lines and cause the shoe tree to fold more easily as it is inserted into the shoe. Ordinarily the body of the shoe tree remains slightly curved in 50 section after the prebreaking operation. The toe end of the shoe tree is then inserted into the shoe and forced forwardly. The edges of the shoe tree adjoining the forward end thereof engage in the shoe at the juncture between the sole and the upper and tend to restrict the 55 width of the shoe tree as it moves forwardly. This causes the center portion of the shoe tree to bow upwardly into channel form as illustrated. When bent in this manner the channel thus formed possesses considerable strength and resistance to folding transversely 60 of the score lines.

When fully inserted the notches 13 engage the counter or back stay of the shoe above the heel, the notches preventing the shoe tree from sliding rearwardly out of position. One size of shoe tree will fit into more than 65 one size of shoe in ordinary practice and still work effectively to hold the shoe in its proper shape.

It will be noted that the top of the shoe tree or the 70 center portion thereof engages beneath the toe cap of the shoe and beneath the instep and hold this portion from creasing transversely. One of the main purposes of such an article is to prevent the sole from curving

upwardly at the toe and creating an unsightly crease or wrinkle across the toe or instep, detracting from the appearance of the shoe when it is sold.

Obviously the shoe trees may be removed for reuse. If the material of which the shoe trees are made is of durable material, the trees will last for an indefinite period. Thus they may be used by the ultimate consumer as well as by the manufacturer.

If the shoe trees are made of relatively thinner material, the score lines may be omitted, although they are extremely important when heavier material is employed. It is also possible to omit the handle portion of the shoe tree, although this handle portion makes the device much easier to insert and remove, particularly if the structure is to be reused.

In accordance with the patent statutes, I have described the principles of construction and operation of my shoe tree, and while I have endeavored to set forth the best embodiment thereof, I desired to have it understood that obvious changes may be made within the scope of the following claim without departing from the spirit of my invention.

I claim:

A shoe tree of foldable material, provided with a central longitudinal bowed portion so that the central portion extends against the top of the toe portion of the shoe and having side edges to engage the sides of the shoe and said shoe tree being provided on its lower part of its rear end portion with notch means to engage the upper rear end of the shoe to hold the shoe tree from sliding rearwardly therein.
